SEALED BOX WITH POURING SPOUT

Carl F. Lundberg, Minneapolis, Minn.

Application October 3, 1940, Serial No. 359,513

10 Claims. (Cl. 229—17)

My invention relates to boxes or cartons of the character or structure especially adapted for containing granular materials such as so-called breakfast foods and the like, and, generally stated, consists of the novel devices, combinations of devices and arrangement of parts hereinafter described and defined in the claims.

Particularly the improved box or carton is adapted to be made from various suitable materials but is especially adapted for making of cardboard or heavy paper boxes or cartons. More especially, the invention relates to such boxes or cartons that are provided with projectable pouring spouts but are normally sealed against the passage of air. The invention is especially directed to the structure of or manner of application to the box of the spout structure and the simple and efficient means for normally sealing the box. The box, including the spout, is adapted to be stamped from a flat sheet of cardboard or the like and to be readily bent to form the box with enclosed spout.

The invention is illustrated in the accompanying drawings wherein like characters indicate like parts throughout the several views.

Referring to the drawings:

Fig. 1 is a view in perspective, with some parts broken away, showing the box and spout-forming sheet bent to form the various elements of the box, said parts being partly bent into box-forming position;

Fig. 2 is a view in perspective showing the box-forming sheet bent to form a complete box with the pouring spout projected into the same, some parts being broken away;

Fig. 3 is a flat or plan view of the sealing sheet or plate that is used to seal the box with the pouring spout within the box;

Fig. 4 is a view partly in section and partly in elevation showing the sealing sheet of Fig. 3 bent approximately into the form it takes when applied to the box;

Fig. 5 is a fragmentary view in perspective showing the top of the box with the sealing strip applied thereto;

Fig. 6 is an enlarged vertical section taken on the line 6—6 of Fig. 5;

Fig. 7 is a view in perspective corresponding to Fig. 6 but showing the upper or final sealing flap or portion of the sealing strip pulled up to expose a portion of the pouring spout for engagement by the nail of a finger or the like;

Fig. 8 is a view corresponding in the line of its section to Fig. 6 but showing the spout partly lifted from closed position;

Fig. 9 shows the spout loosened and turned into a pouring position; and

Fig. 10 is a view in perspective corresponding to Fig. 2 but illustrating a somewhat modified structure wherein the paper sealing strip is not employed.

Referring first to the preferred construction illustrated in Figs. 1 to 8, inclusive, Fig. 1 shows the box proper which, as stated, is made from a single sheet, preferably and assumed to be a quite heavy cardboard. This sheet has curved or creased bending lines that adapt the sheet to be bent to form flat wall portions, to wit: side plates 12 and 13, end walls 14 and 15, and sealing flap 16, which latter projects from the end wall 15 and is adapted to overlap the end wall or plate 13. The bottom of the box is formed by flaps 12a, 13a, 14a and 15a that are integral lower extensions of the said members 12, 13, 14 and 15, respectively. These flaps 12a, 13a, 14a and 15a are adapted to overlap, as shown in Fig. 2, to close the bottom of the box. The sealing flap 16 will overlap and be adhesively or otherwise secured. At the top of the box the wall plate 12 is formed with a flap 12b that is adapted to be lapped with flaps 13b and 14b, respectively, on the wall or plate portions 12, 13 and 14.

The pouring spout is formed by extensions of the upper end of the end wall 15 and comprises a plate portion 17 with side flanges 18. When the box is closed the plate portion 17 will overlap the then overlapped and interlapping flaps 12b, 13b and 14b and in the particular arrangement shown in Fig. 1, the free end of plate 17 will rest upon the flap 13b and will complete the closing of the top of the box. When the pouring spout is turned outward, as shown, or into pouring position, as shown in Fig. 9, its outward movement will then be limited by projections 17a on the side flanges or plates 18 which then engage the undermost of the overlapped flaps 12b, 13b and 14b.

The box so far described would be an operative container with an extensible pouring spout and which spout, when closed, would close the box, but the box would not be hermetically sealed without the addition of some sealing means. In the preferred structure illustrated in Figs. 1 to 8, inclusive, novel sealing means for the above purpose is provided. The sealing strip or sheet preferably employed is made of thin but quite tough paper which, when laid out flat, see Fig. 3, involves a main body portion 19 with side flaps 20, one end flap 21, and at the other end an extended portion 22 that is creased and adapted to

be bent to form a U-folded pulling flap 23 and a depending lap flap 24, see Figs. 4 and 6.

The contracted or neck portion of the connection between the members 19 and 22 is preferably perforated at 25 to form a tearing line. When this sealing strip, bent as shown in Fig. 4, is applied on the top of the box, the flaps 20 21 and 24 will overlap and be adhesively secured to the sides and top of the box and the plate portion 22 will be adhesively secured to the top of the plate 17 of the pouring spout, and thus the box will be normally hermetically sealed. Here it is important to note that when the sealing strip or plate is applied as just described, the under-turned portion 22 of the sealing strip will cover and be co-extensive with the plate 17 of the pouring spout and the free end of the latter will be covered by the sealing strip.

To provide simple means for exposing the free end of the said plate 17 so that it can be engaged, for example, by a finger nail as shown in Fig. 8, the upper portion of sealing strip 19 is perforated on lines 26. These perforations extend from the pulling flap 23 to a place beyond the free end of the plate 17. When the box is to be opened by a movement of the pouring spout to a pouring position that portion of the sealing strip that is within the perforated lines 26 is pulled loose and turned upward and, if preferable, entirely removed, see Fig. 7, thereby exposing the free end of the plate 22 to its engagement, such as shown in Fig. 8, so that the pouring spout may be raised and turned outwardly simply by breaking through the body 19 of the sealing strip. To make this movement of the pouring spout an easy and practical matter, the body portion 19 of the sealing strip is provided with outer and wider spaced perforated lines 27 that follow the sides of the spout plate 17 and extend somewhat beyond the free end thereof. These perforated or weakened lines 27 make it easy for the spout plate 17 to tear its way through the sealing strip.

As is evident, the sealing strip applied as described affords a thoroughly hermetically sealed package for containing various articles indicated and after the seal has been broken, affords means for conveniently pouring quantities from the container and then again fairly well sealing the same simply by turning the spout back to closed position.

The box shown in Fig. 10 is or may be assumed to be the identical box above described with an added feature intended to securely hold the spout in closed position even after the hermetic seal has been broken. This added device involves an elastic band 28, a portion of which is anchored to the sides of the box by adhesively applied paper strips 29. Normally, or when the box is sold, the band will be applied, as shown by full lines in Fig. 10, but when the seal has broken and it is desired to hold the spout closed, a loose portion of the band is applied over the top of the spout plate 17, as shown by dotted lines in Fig. 10.

From the foregoing it will be understood that the device described is capable of modifications within the scope of the invention herein disclosed and claimed.

The pouring spout and seal are herein referred to as being applied to the top of the box, but it will be understood that that statement is used in an illustrative sense and that the said spout and seal might be applied to other walls of the box or container.

What I claim is:

1. A box of the kind described provided with a projectable pouring spout, the spout bottom-forming plate of which, when the spout is closed, forms a part of the top of the box, and a fragile sealing strip applied to the box and covering the otherwise exposed bottom-forming plate of the spout, said sealing strip having a portion united thereto by fragile tearing lines that extend beyond the free end of said bottom-forming plate, the said sealing strip normally entirely covering and extending beyond the area of the bottom-forming plate of said spout and completely sealing the same.

15 2. A box of the kind described provided with a projectable pouring spout hinged to one of the walls of the box, the spout bottom-forming plate of which, when the spout is closed, forms a part of the top of the box, and a fragile sealing strip applied to said box and covering the otherwise exposed bottom-forming plate of the spout, said sealing strip having a portion united by fragile tearing lines that substantially follow the outline of said bottom-forming plate, and further having within the area covered by said last noted fragile tearing lines, other tearing lines covering less area but extended beyond the free end portion of said bottom-forming plate.

30 3. The structure defined in claim 2 in which the part of said sealing strip within said tearing lines is terminated at the edge of the box in a folded pulling flange.

4. The structure defined in claim 2 in further combination with a flexible band attached to said box with a portion thereof free for application over the spout bottom-forming plate to hold said spout against accidental opening movements.

5. A box of the kind described provided with a projectable pouring spout, the spout bottom-forming plate of which, when the spout is closed, forms a part of the top of the box, and a fragile sealing strip applied to the box and covering the otherwise exposed bottom-forming plate of the spout, said sealing strip having a portion united thereto by fragile tearing lines that extend beyond the free end of said bottom-forming plate, and which fragile sealing strip is folded upon itself to form an underlying portion of substantially the same outline as said spout bottom-forming plate.

50 6. A box of the kind described provided with a projectable pouring spout, the spout bottom-forming plate of which, when the spout is closed, forms a part of the top of the box, and a fragile sealing strip applied to the box and covering the otherwise exposed bottom-forming plate of the spout, said sealing strip having a portion united thereto by fragile tearing lines that extend beyond the free end of said bottom-forming plate, and in which the part of said sealing strip within said tearing lines is terminated at the edge of the box in a folded pulling flange.

65 7. A box of the kind described provided with a projectable pouring spout, the spout bottom-forming plate of which, when the spout is closed, forms a part of the top of the box, and a fragile sealing strip applied to the box and covering the otherwise exposed bottom-forming plate of the spout, said sealing strip having a portion united thereto by fragile tearing lines that extend beyond the free end of said bottom-forming plate, and in further combination with a flexible band attached to said box with a portion thereof free for application over the spout bottom-forming plate to hold the spout against accidental opening movements.

8. A box of the kind described provided with a projectable pouring spout, the bottom-forming plate of which, when the spout is closed, forms a part of one wall of the box, a sealing strip applied to the box and normally completely covering and sealing the otherwise exposed bottom-forming plate of the spout, said sealing strip having a portion united thereto by a fragile tearing line that closely follows the outline of said bottom-forming plate, and an additional sealing strip of less area than said first noted sealing strip having tearing lines extended to the extreme inner portion of the tearing line of said first noted sealing strip.

9. The structure defined in claim 8 in which the tearing lines of both of said sealing strips extend to a point beyond the inner end of the bottom-forming plate of said spout.

5 10. The structure defined in claim 8 in which the tearing lines of both of said sealing strips extend to a point beyond the inner end of the bottom-forming plate of said spout, said last noted sealing strip having a flange projecting at the adjacent edge of the box and adapted to be gripped to initially tear out said second noted sealing strip.
